UNITED STATES PATENT OFFICE.

BENJAMIN FRANKLIN STEEL, OF EAST ORANGE, AND HARRY DANIEL KELLY, OF BLOOMFIELD, NEW JERSEY, ASSIGNEES TO WESTINGHOUSE LAMP COMPANY, A CORPORATION OF PENNSYLVANIA.

MACHINE FOR TREATING WIRE.

Application filed July 13, 1922. Serial No. 574,615.

This invention relates to a machine for coating wire and relates more particularly to machines employed for borating various sizes of wires for use in the manufacture 5 of incandescent electric lamps.

An object of the invention is to expedite the coating of wire in an economic and efficient manner.

Another object is to provide a machine 10 in which wire may be given an automatic continuous treatment.

A further object is to provide a machine adapted to coat a plurality of wires simultaneously or to coat such wires singly.

15 Other objects and advantages of the invention will be apparent upon a reading of the following description.

Although our invention may be employed for the treatment of various kinds 20 of wires it is described and illustrated as operating to treat a copper clad wire such as used as electric current conductors in incandescent electric lamps. Conductors of the above character are generally sealed 25 into a lamp and it has been found that a more efficient union of the wire and glass is produced when the wire has been given a treatment consisting of heating and immersion in a borax solution, a coating of 30 borax being thus deposited on the wire. This coating promotes the wetting of the wire by the plastic glass and tends to produce an efficient union.

Machines for coating a wire by immersion in a bath have heretofore been so constructed that an excessive amount of floor 35 space was required and constant expert attention on the part of an operator was necessary in order to keep the apparatus in 40 continuous operation.

The present invention provides a machine which multiplies the number of lineal feet 45 per minute that may be treated and performs its functions automatically with a minimum amount of attention from an operator and with the utilization of a relatively small amount of floor space. Furthermore, the machine is so constructed that considerable saving in fuel is attained, it being possible 50 to employ a single burner in place of the two separate burners that have heretofore been necessary. The number of elements necessary to construct the apparatus has also been reduced, with a consequent re-

duction in the initial cost and in the cost 55 of maintenance.

Our invention also provides for the uniform and continuous travel of the wire and for the uniform and even distribution of heat during the pre-heating and subsequent 60 drying operations, with the result that a more efficient and evenly distributed coating is obtained.

The embodiment of our invention shown and described comprises a wire-coating apparatus which preferably comprises four separately operable devices, each of which may be independently actuated to draw a wire from a spool over a burner for pre-heating and into a solution for coating, thence over a burner again for a baking operation, means being provided to finally receive the wire. Two or more of the devices may operate to immerse a wire in a single tank and all of the devices are preferably driven from a single source of power and may be simultaneously operated to propel wire through a solution or they may be operated individually, suitable clutch mechanisms being provided whereby either of 70 the devices may be disengaged from the main drive and its operation terminated 75 while the remaining units may be continuously driven.

Referring to the accompanying drawings, 85

Fig. 1 is a diagrammatic plan view showing the positions of the various operative parts of the machine;

Fig. 2 is a side view, in elevation, of the machine, partly in section to show the burners;

Fig. 3 is a view, in elevation, of a duplex winding head, partly in section to show the spool bearings;

Fig. 4 is an end view, in elevation, of the structure shown in Fig. 3;

Fig. 5 is an enlarged detail view of a chuck which controls the winding spools of the head shown in Fig. 3 and is shown partly broken away to disclose the clutch;

Fig. 6 is a sectional view of a tank which may contain a wire-treating solution and also shows wire-guide wheels and their adjustable support; and,

Fig. 7 is a sectional view taken on line VII-VII of Fig. 2, enlarged, and illustrates the position of the wires as they pass over the heating element.

- The machine may include a table 11 having mounted thereon one or more winders or winding heads for winding wire. In the present embodiment of the invention, two 5 winding heads are employed and each is designated, as a whole, by the numeral 12. The operation and construction of these heads will be hereinafter more fully described.
- 10 Mounted on the table 11, in an operative relation to each of the winding-heads, is a bracket 13 having a bearing in which a spindle 14 is journaled. The spindles 14 have feed rollers or spools 15 rotatably positioned thereon. The rollers may be removable and carry the wire which is to be treated. The wires driven by the left-hand winding-head are indicated by the numeral 16, and the wires driven by the right-hand 15 head are indicated by the numeral 16'.
- Suitably positioned on the table 11 with respect to the winding-heads is a tank or container 17 which may contain a solution in which the wire is to be immersed for treatment. It is desirable to heat the wire previous to its entrance into the solution and for this purpose, heat zones are created by means of burners 18 disposed within trough-shaped casings 19. The casings or 20 ovens are secured to posts 21 and 22 having bolts 23 and 24 movable in slots 25 and 26 suitably positioned in the respective posts. Thus, a vertical adjustment of the oven may be had. It is also desirable to heat the solution and, for this purpose, a burner 27 is 25 provided. The burners may be of the Bunsen type and be connected to any suitable source of fuel by a conduit 28, and hand-operated valves 29 and 31 may be provided for controlling the supply of fuel. Suitable 30 levers 32 and 33 for manipulating the valves may be conveniently located above the surface of the table 11. The pilot lights 28', 29' and 30 may be provided for lighting the burners after a complete or partial shutdown of the machine.
- After the wire 17 leaves the spool 15 of the winding-head at the left-hand end of the machine, it is moved in the directions indicated by the arrows and passes over a sheave 34, mounted on a suitable support, and through the heat zone created by the burner 18, thence in the groove of a guide or idler 36 and around a pulley 37. Its path of movement is thus reversed, and it then takes an opposite course of travel and again passes through the heat zone created by the burner 18, for a drying operation, then over a sheave 38 which is spaced away 35 from the sheave 34, as indicated in Fig. 1. Another idler 36' and a pulley 37' are provided to reverse the direction of movement of another wire driven by the winding-head at the opposite end of the machine. The 40 wire is, therefore, maintained in spaced re-

lution throughout its movement through the heat zone. It will be noted that the angular disposition of the idler 36 and the pulley 37 provide for the spacing of the wire as it leaves and enters the tank and that the relative positions of the idler 36, pulley 37 and the sheaves 34 and 38 serve to maintain the sections of wire in a common plane.

The idlers and pulleys are carried on a bracket 39 which is suitably secured to the table 11 (see Fig. 6). This bracket is provided with an overhung portion 41 having slots 42 in which are positioned bolts 43 having winged nuts 44 at their exposed ends and suitably proportioned heads 45 at the other ends. The heads are positioned for frictional engagement with one side of the portion 41. The bolts 43 pass through carriers 46 which comprise a pair of depending and independently adjustable bearings 47 and 48. One of the carriers supports the idler 36 and the pulley 37 and the other carrier supports the idler 36' and the pulley 37'. These bearings 47 and 48 are disposed in different planes, and the pulley 37 50 serves as a means for reversing the direction of movement of the wire 17 while the pulley 36' serves the same purpose for the wire 16' which may be driven by another winding device.

The idler 36 and the idler 36' are rotatable about pins 49 secured in forked members 51. These members extend through arms 52 positioned at opposite sides of the carriers 46. The members 51 are suitably secured in the arms by set screws 53. The arms 52 are split and may be clamped to properly disposed rods 54 integral with the carriers 46. By loosening the screws 53, the members 51 may be adjusted to vary the distance between the transverse axes of the idlers and the pulleys or by a movement of the arms 52 along the rods 54; the idlers and the pulleys may be disposed in a variety of different inclined planes. By an adjustment of the idlers 36 and 36' the wire may be led through the solution in a shorter or longer path. This is evident from the fact that a variation in the positions of the idlers changes their spaced relation with the respective reversing pulleys 37 and 38.

In practice, it is often necessary to rethread the wire over the pulleys, as, for instance, in the event that a wire should break during treatment. Considerable inconvenience and loss of time has resulted heretofore, as it has been necessary to remove the solution or perform this tedious operation of threading the wire over the pulley while in the solution.

In the present invention, in the event of a wire breaking, the winged nut 44 may be loosened and a carrier, as 46, slid up on the portion 41 of the bracket 39. A handle 55 is provided on each carrier for the con-

venient manipulation of the carrier. The idlers and pulleys thus being removable from the solution, the wire may be readily led thereover and the carrier again moved 5 to position the pulleys and idlers within the solution.

After leaving the sheave 38, the wire 16 encircles a driving pulley 56 in a bight (see Fig. 3). This pulley is driven by means 10 to be hereinafter described and serves to maintain uniform the speed of movement of the wire. The driving pulleys constitute component parts of the winding-heads which may include a bracket 57 suitably secured 15 to the table 11 by bolts 58. These winding heads are of a duplex character and operate receiving spools 59 and 61.

The present invention employs two such heads and, since their parts and operations 20 are similar, a description of one will answer for both.

The spools 59 and 61 are mounted on shafts 62 and 63 journaled in bearings 64 and 65 integral with the bracket 57. Each 25 shaft has secured thereto, a sleeve 66, and the driving pulleys 56 are, in turn, secured to the sleeves. The spools 59 and 61, upon which the wire is wound after treatment, are frictionally secured to the sleeves 66 by 30 means of helical springs 67 disposed about the sleeves and between, and in contact with, lock nuts 68 and ends of the spools, which are loosely mounted on a bushing 69 to run free or be frictionally connected to the sleeve 35 66. By this frictional engagement, the spools may slip to compensate for the variation in their relative speed as their effective diameter changes during the accumulation of wire thereon.

Each winding head is adapted to permit 40 the rotation of the spools 59 and 61 either simultaneously or individually, and, for this purpose, a double-clutch mechanism is provided. This clutch mechanism is clearly 45 shown in Figs. 3 and 5 and includes an annulus 71 loosely fitted upon, and spanning, the abutting ends of shafts 62 and 63. Journaled upon the annulus 71 is a chain sheave 72. Contiguous with the sheave and secured 50 to the shafts 62 and 63 are disposed collars 73 and 74 to prevent longitudinal movement of the sheave 72 which may, therefore, run free about the shafts. For the purpose of driving either or both of the shafts, the 55 sheave is provided with a plurality of spaced pins 75 which project on each side thereof and are disposed in circular formation. Each shaft has mounted thereon a grooved sliding collar 76 having one of its ends which is adjacent the sheave 72 notched for the reception of the projecting ends of the pins 75.

The collar may be moved into or away 60 from engagement with sheave 72, suitable keys 77 being provided to prevent rotation

of the collars relative to the shaft. The clutches may be manually manipulated by means of levers 78 each of which is pivoted on a bolt or pin 79 secured in the bracket 57. One end of each of the levers is bifurcated 70 to embrace the collars and engage therewith in the usual manner. It will, therefore, be understood that the manipulation of the levers 78 may cause either of the receiving spools to rotate or stop independently of the 75 operation of the other.

As indicated in Fig. 2, the force for driving the various parts of the device is derived from a motor 81 provided with any suitable form of reduction drive 82. Chain sprockets, one of which is indicated by the reference numeral 83, may be provided, and the winding device at the left hand side of the machine may be driven by means including chain 84 which drives a sheave 85 carried 85 on a counter-shaft 86 secured in a bearing 87 fastened to the underside of the table 11. The counter-shaft 86 may also be provided with an additional sheave over which an endless chain 88 is led and which may extend over a guide sheave 89 and thence over the chain sheave 72 of the clutch and over an additional guide sheave 91. The winding device at the right of the machine is driven by similar connections. 95

Referring again to one of the winding heads (see Fig. 3) it is shown that, after the wire leaves the driving pulley 56, it may pass over a guide pulley 92 and thence over a reciprocative pulley 93 and on to spool 59 100 or spool 61. The guide pulleys 93 are carried on shafts 94 which are off-set from, and connected to, a reciprocating shaft 95. The shaft 95 is reciprocated by means of its connection to a cam follower 96 disposed in a double-cam-surface wheel 97. The cam follower is secured to an arm 98 which is fastened to the shaft 95. Reciprocation of the shaft is produced by rotation of the wheel 97 which is fastened to a shaft 99 provided with a worm wheel 101 disposed in mesh with a worm 102. The worm 102 is secured to a vertical shaft 103 suitably journaled in a bearing in the table 11. The shaft extends 110 downwardly and has secured at the lower end thereof, a bevel gear 104 (see Fig. 2) in mesh with a bevel gear 105 secured to a transverse shaft 106 suitably journaled in bearings of a bracket 100 secured to the 115 table 11. 120

The shaft 106 is driven by means comprising a chain sheave 107 secured thereto which is, in turn, driven by an endless chain 108 which engages a suitable sheave fastened to the counter-shaft 86. Motion is thereby 125 translated to the reciprocating pulley 93.

In operation, considering one operative portion of the machine, a spool of wire is mounted on the bracket 13 and the wire is led over the sheave 34 and through the heat 130

zone and thence around the idler 36, around the pulley 37, back through the heat zone; over the pulley 38 and thence around the driving pulley 56, over the idler 92 and over 5 the reciprocating pulley 93 from whence it is guided for uniform disposition upon spool 59 or spool 61.

Upon an inspection of Fig. 1, it will be observed that although four different spools 10 of wire may be treated, only two tanks for the baths are required and that only two winding devices are necessary. Furthermore, a single heat zone suffices for the pre-heating and final heating or drying the 15 wire. By this arrangement of the various operative parts of the present machine, increased output, greater uniformity of product and economy of floor space are attained.

Although the preferred embodiment of 20 the invention is shown and described herein, it is obvious that many other modifications may be made therein without departing from the spirit and scope of the appended 25 claims.

25 What is claimed is:

1. A machine for coating wire comprising a support for a spool of wire, a tank having 30 a solution therein, a reversing pulley adjustably supported and immersed in said solution to receive and reverse the direction of movement of said wire and adjustable means to guide the wire over said reversing pulley, said means being adapted to guide the moving wire in a longer or shorter path 35 through said solution.

2. A machine for coating wire comprising a support for a spool of wire, a tank having a solution therein, a reversing pulley adjustably supported and immersed in 40 said solution to receive and reverse the direction of movement of said wire, an idler

pulley adjustably disposed to guide the wire over said reversing pulley, said idler pulley being adapted to guide the moving wire in a longer or shorter path through said solution. 45

3. A machine for coating wire comprising supports for a plurality of spools of wire, a tank having a solution therein, means for moving wires from spools held on said supports, a plurality of reversing pulleys immersed in said solution, a common support for said pulleys, means for adjusting the position of said support within said tank, guides arranged to direct wire passing into 50 said solution and to said reversing pulleys, means for adjusting the guides to vary the lengths of the paths of travel of the wires through said solution.

4. A machine for coating wire comprising 60 a plurality of supports for spools of wire, winding mechanisms disposed adjacent to each of said supports, a tank having a solution therein, a plurality of heating elements positioned adjacent to said tank, wire reversing members mounted on an adjustable support and immersed in said solution, means for guiding wire over said heating elements to said reversing members, means for guiding wire in a reverse direction over 70 said heating elements and means disposed adjacent to said reversing members for guiding the wires into and out from said solution and said last mentioned means being adjustable to change the path of movement of said wires. 75

In testimony whereof, we have hereunto subscribed our names this 12th day of July, 1922.

BENJAMIN FRANKLIN STEEL.
HARRY DANIEL KELLY.
